CLAIM

The ornamental design for a car or similar article, as shown and described.

DESCRIPTION

FIG. 1 is a front perspective view of a vehicle showing my new design;

FIG. 2 is a rear perspective view thereof;

FIG. 3 is a front elevational view thereof;

FIG. 4 is a rear elevational view thereof;

FIG. 5 is a side elevational view thereof; and

FIG. 6 is a top plan view thereof.

The unshown bottom of the design is substantially plain and unornamented.

*FIG. 1**FIG. 2*

*FIG. 3**FIG. 4*

FIG. 5

FIG. 6
